UNITED STATES PATENT OFFICE.

PAUL KAULFUSS, OF PENIG, GERMANY.

FLUID-MEASURING APPARATUS.

SPECIFICATION forming part of Letters Patent No. 417,563, dated December 17, 1889.

Application filed November 21, 1888, Serial No. 291,518. (No model.) Patented in Germany October 30, 1888, No. 47,733; in England November 7, 1888, No. 16,151, and in Austria-Hungary February 8, 1889, No. 45,158 and No. 1,044.

To all whom it may concern:

Be it known that I, PAUL KAULFUSS, manufacturer, a subject of the Emperor of Germany, residing at Penig, in Germany, have 5 invented certain new and useful Improvements in Fluid-Measuring Apparatus, (the same having been patented in England, No. 16,151, dated November 7, 1888; in Germany, No. 47,733, dated October 30, 1888, and in 10 Austria - Hungary, No. 45,158 and No. 1,044, dated February 8, 1889,) of which the following is a specification.

The present invention relates to an apparatus by means of which fluids can be drawn 15 from barrels or other vessels in predetermined quantities, the apparatus closing automatically when the desired quantity has passed.

In the accompanying drawings, Figure 1 20 represents a vertical section of the apparatus with closed valves. Fig. 2 represents a similar view with open valve. Fig. 3 represents a plan, the graduated disk being removed. Fig. 4 represents a front view, partly in section, the section being on line II, Fig. 2. Fig. 25 5 represents a section of the measuring-valve and the measuring-vessels on line II II of Fig. 2. Fig. 6 represents a plan of the graduated disk.

The invention consists, essentially, in the 30 employment of two measuring-vessels M, capable of holding a certain quantity of fluid, and which are connected with a conical sleeve H, surrounding and oscillating on the stationary conical tube K of the valve. These 35 measuring-vessels are alternately filled and emptied until the desired and predetermined quantity of the fluid has passed out of the apparatus. The alternate filling and emptying of the measuring-vessels M is effected by 40 the conical tube K, being formed with one inlet-opening E, and two outlet-openings A, which are separated from the inlet by a partition in the said conical tube. Each of the 45 measuring-vessels M will register or communicate with the inlet E when it is empty and with one of the outlets A when it is filled. To fill the vessels M, the valve V must be opened.

The oscillating movement of the vessels M

with the sleeve H for the simultaneous filling and emptying the vessels is automatic. The vessel M, which at the time is upright, and with the whole of the oscillating mechanism, is held in position by one of two pivoted catches k, engaging with a pin z of the vessel M. When the vessel is perfectly filled, the fluid contained therein lifts the air-valve L, which closes, and by means of its spindle l lifts the before-mentioned catch k, and 60 disengages this from the pin z, so that the vessel M, weighted by the fluid it contains, falls from the upright into an inclined position. This movement is limited by one of the arms Q, one of which is fixed to each vessel, coming in contact with a rib R on the rigid body of the apparatus, and the spiral spring F serves to decrease the force of the fall and to take up all jerks, said spring for 65 this purpose being connected to a stationary 70 central stud or projection F² on the frame at one end, and to the upper end of the guide-arms C on the chambers. Thus when said guide-arms move to either side the spring is drawn out and exerts its force to stop the 75 movement of the chambers, as just mentioned. Another spiral spring f, Fig. 1, is interposed between the sleeve H and a flange of the outlet-tube O, screwed on the conical tube K, and tends to press the sleeve H farther up on 80 the tube K, so that the sleeve H always fits closely on the said tube.

The number of the oscillations of the vessels M depends upon the quantity of the fluid to be withdrawn. During one reciprocating 85 movement two fillings and two emptyings will take place, so that if, for instance, each of the vessels M holds one-eighth of a quart and three quarts are to be drawn off twelve reciprocating movements will have to take 90 place.

For the automatic closing of the valve after the passing out of the desired quantity of liquor a separate mechanism and a graduated scale are provided, the said mechanism being 95 actuated by the movement of the vessels M. Between the vessels M and oscillating with them is a guide C, between the arms of which projects the bent end of the pivoted lever P, provided at its upper end with a weighted 100

pawl S, engaging with a ratchet-wheel Z. From Fig. 4 it can be seen that when the vessels M oscillate to the right the pawl S will move the ratchet-wheel Z to the left for 5 the space of one tooth, while when the vessels oscillate to the left the pawl will merely be moved over one tooth to the right. Each tooth, therefore, represents one reciprocating movement of the vessels M, and it follows 10 therefrom that in starting the apparatus the vessel at the left side must be in the upright position. Each movement of the ratchet-wheel Z moves the indicator Y over the graduated scale to the extent of one degree 15 until the indicator arrives at the zero of the scale, when the valve will be automatically closed.

The indicator Y is fastened to a handle U, which is attached to the disk R', carrying the 20 ratchet-wheel Z and revolving within the casing G. By means of this handle the ratchet-wheel can be turned after the pawl S has been disengaged by depressing the small arm d connected with it. Above and concentric with the revolving disk R' is mounted 25 on short uprights t the circular graduated scale T, over which passes the indicator Y. If it is desired, for instance, to draw off four quarts, the indicator is placed over 4 of the 30 scale.

As described above, with each reciprocating movement of the vessels M the disk R', with the indicator Y, is moved to the left for 35 the space of one tooth until the indicator reaches the zero on the scale, when the valve will be closed and the apparatus stopped automatically, as will now be explained.

If desired, the circular scale may be replaced by a straight scale by suitably modifying the mechanism.

To start the apparatus, the indicator is adjusted on the scale according to the quantity desired to be drawn off, and the valve V is then opened by depressing the button W, as 45 indicated in Fig. 2. This valve, which in its normal position is maintained closed by means of the spiral spring x, must be held open during the operation of the apparatus. To this end the valve-spindle is provided 50 with a collar Y, having a flange b, on which bears one projection or nose of a pivoted nut or tumbler n. When the valve-spindle is being depressed, the flange b turns the tumbler n by means of the small arm a, fixed to the 55 said tumbler, and the end of the pivoted lever h, held depressed by weight g, secured to its pivot, as shown in Figs. 3 and 4, will engage with another projection or nose of the tumbler n, thus keeping the valve-spindle 60 depressed and the valve open by the depressed nose of the tumbler bearing against the top of the flange b of the valve-spindle. The handle U is further provided with a beveled or inclined projection B, which rides up on the 65 free end of the pivoted lever h and depresses this at the moment when the indicator Y ar-

rives at the zero of the scale, thereby releasing the weighted end of the lever h and unlocking the tumbler n, when the valve V will be instantly closed under the influence of 70 the spiral spring x.

By means of its flange c the apparatus can be easily attached to the vessel from which the fluid is to be drawn off, or, if desired, it can be secured to a tube leading out from 75 such vessel. A ball i, introduced into the tube of the apparatus, serves to regulate the pressure and passage of the fluid. Each of the measuring - vessels M is moreover provided with a short tube or socket having a 80 screw cap or a plug e screwed onto it, by means of which the capacity of the vessels may be corrected and adjusted.

I claim—

1. In a fluid - measuring apparatus, the 85 combination, with the oscillating measuring-chambers and spring-pressed valve for automatically cutting off the supply thereto, of the catch for holding said valve open, and operated by the oscillating chambers to release the valve, substantially as described.

2. In a fluid - measuring apparatus, the combination, with the oscillating measuring-chambers and the valve controlling the supply thereto, of the valve-retaining catch, and 95 the adjustable trip therefor operated by the oscillating chambers to release the valve, substantially as described.

3. In a fluid - measuring apparatus, the combination, with the oscillating measuring-chambers and the spring-pressed valve controlling the supply thereto, of the valve-retaining catch and lever, the tripping-cam, the adjustable ratchet-wheel on which said cam is mounted, and the pawl operated by the 105 oscillating chambers to move said wheel to release the retaining catch and lever, substantially as described.

4. In a fluid - measuring apparatus, the combination, with the oscillating measuring-chambers, the spring-pressed valve controlling the supply thereto, and the handle for depressing the valves, of the catch and lever for retaining the valve depressed, the tripping-cam having the arm thereon, the index 115 with which said arm registers, the adjustable ratchet-wheel on which said cam is mounted, the pawl engaging the ratchet-wheel, and the arm operated by the chambers for moving the cam, substantially as described.

5. In a fluid - measuring apparatus, the combination, with the oscillating measuring-chambers, the spring-pressed valve controlling the supply thereto, the valve-stem having the collar or flange thereon and the handle for depressing the valve, of the pivoted catch engaging said collar or flange on the valve-stem, the lever engaging said catch to hold the valve down, the ratchet-wheel having the tripping-cam for releasing the lever 130 mounted thereon, the pawl engaging said ratchet-wheel, and the arm operated by the

oscillating chambers for moving said pawl, substantially as described.

6. In a fluid - measuring apparatus, the combination, with the oscillating measuring-chambers with the entrance and discharge ports automatically controlled by the movement thereof, of the catches for retaining said chambers in upright or filling position, the valve-openings in the upper ends of said chambers, the floats forming the valves for closing said openings, and the valve-stems

engaging the catches to release the chamber when full and the valve closed, substantially as described.

In testimony whereof I have hereto set my hand in the presence of two subscribing witnesses.

PAUL KAULFUSS.
